UNITED STATES PATENT OFFICE

2,518,636

KILN

Harvey Phillips, Malvern, Ark., assignor of twenty-five per cent to Willie A. Riggs, Malvern, Ark.

Application February 25, 1948, Serial No. 10,670

9 Claims. (Cl. 259—82)

1

This invention relates to new and useful improvements in kilns and the primary object of the present invention is to provide a kiln including novel and improved means for removing sedimentation rings formed on the inner walls of the same.

Another important object of the present invention is to provide a kiln including a plurality of agitating baffles mounted therein and including novel and improved means for agitating the baffles within the kiln to retain the inner walls of the kiln free from foreign matter and sedimentation which usually forms thereon during the operation of the kiln.

A further object of the present invention is to provide a kiln embodying means for frictionally supporting the kiln during the rotation of the same in use.

A still further aim of the present invention is to provide a kiln that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a fragmentary perspective view of the present invention, and with parts thereof broken away and shown in sections;

Figure 2 is a longitudinal sectional view taken substantially on the plane of broken section line 2—2 of Figure 1;

Figure 3 is a fragmentary transverse vertical sectional view taken substantially on the plane of broken section line 3—3 of Figure 1, and with parts thereof broken away and shown in sections; and,

Figure 4 is an enlarged fragmentary sectional view of the upper portion of the present invention, taken substantially on the plane of section line 4—4 of Figure 2.

Referring now to the drawings in detail, wherein for the purpose of illustration, there is disclosed a preferred embodiment of the present invention, the numeral 10 represents an elongated cylindrical container or kiln that is open at both ends to receive suitable removable closures (not shown), and which is provided with an inner lining or sleeve 12 of any suitable material.

A plurality of longitudinally and circumferen-

tially spaced apertures 14 are provided in the container 10 and lining 12 and these apertures 14 each frictionally support guide sleeves 16 having stop flanges 18 that prevent inward movement of the guide sleeves 16 relative to the container 10. Mounted in each of the guide sleeves 16 for reciprocating movement, is a plunger or support arm 20, the inner end 22 of which extends into the container 10 and is removably secured in any suitable manner to the ends of a plurality of longitudinally extending, circumferentially spaced agitator, crustation breaker plates 24.

Secured by welding or the like to the outer ends 26 of the support arms 20, are substantially U-shaped support plates 28 that rotatably support bearing rollers 30. Coil springs 32 loosely embracing the support arms 20 and biased between the stop flanges 18 and the support plates 28, normally retain the support arms in an outwardly extended position, as shown best in Figure 4 of the drawings.

The numeral 34 represents the container supporting block used in conjunction with the present invention generally, each of which comprise a base portion 36 that is removably secured to a supporting structure 38 by fasteners or the like 40, and a pair of spaced side walls 42 and 44. The side walls 42 and 44 are provided with opposed central, arcuate notches 46, pairs of opposed humps 48 adjacent the notches 46 that rotatably support rollers 50. Integrally formed at the ends of the side walls 42 and 44, are end walls 52 which are bifurcated at their upper ends 54 to rotatably support further rollers 56. It should be noted, that the rollers 50 and 56 frictionally engage and support the container 10, and that a plurality of supporting blocks 34 are used in conjunction with the container 10 and are so disposed as to be spaced relative to the rollers 30 and support plates 28 carried by the support arms 20, whereby the container may rotate freely upon the rollers 50 and 56 without the said supporting blocks 34 coming in contact with any type of obstruction carried by the container 10.

Embedded in the ground or a supporting structure 38, is a plurality of longitudinally spaced, preferably I-beams or uprights 58 each of which rigidly supports horizontally disposed I-beams or hanger arms 60 that are fixed to the uprights 58 by brace plates 62. Rigidly secured to the lower faces of the hanger arms 60 are cams 64 which are disposed above the container 10 and which frictionally engage the rollers 30 upon rotation

of the container 10 to reciprocate the arms 20 and thus effect an inward and outward movement of the agitator plates 24 to remove sedimentation rings formed on the inner walls of the lining 12.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A kiln comprising a container, means disposed completely within the container and movable laterally of the container for removing sedimentation formed on the inner walls of the container, means slidably carried by the container for agitating said sediment removing means and means engaging said last-mentioned means during rotation of said container to actuate said second-named means.

2. A kiln comprising a container, means mounted in said container for lateral movement with respect to the container to remove sedimentation formed on the inner walls of the container, means for supporting said container during the rotation thereof, means disposed radially of and slidably carried by the container and connected to the first-mentioned means for agitating said sediment removing means, and means engaging and actuating said second-mentioned means during rotation of said container.

3. The combination of claim 2 wherein said means for removing sedimentation formed on the inner walls of the container includes a plurality of longitudinally disposed circumferentially spaced crustation breaker plates terminally secured to said second-mentioned means.

4. The combination of claim 1 wherein said last-mentioned means includes a frame, cam means carried by said frame and said agitating means including plungers carried by said container operatively connected to said sedimentation removing means, means normally urging said plungers from said container, and means carried by said plungers for frictionally engaging said cam means.

5. The combination of claim 4 wherein said last mentioned means includes a roller carried by each of said plungers.

6. The combination of claim 2 wherein said

supporting means includes a plurality of support blocks, and rollers carried by said blocks for frictionally engaging the outer periphery of the container.

5. A kiln comprising a substantially cylindrical container, agitator plates mounted in said container for removing sedimentation rings formed on the inner walls of the container, reciprocable plungers slidably carried by the walls of the container and connected to said agitator plates, rollers carried by said plungers, supports disposed adjacent said container, and cams carried by said supports for engaging said rollers upon rotation of said container, said plungers being disposed radially of said container and said plates being mounted in said container for lateral movement relative to the container, said plates being terminally secured to said plungers.

6. The combination of claim 7 wherein said agitator plates are sequentially agitated during rotation of said container.

9. A kiln comprising a support having rollers mounted thereon, a cylindrical container supported on said rollers for rotation, a first group of circumferentially spaced elongated plates received in said container, a second group of circumferentially spaced elongated plates received in said container, said second group of plates being staggered with respect to the first group of plates, each plate of both groups of plates having inner and outer end portions, the inner end portions of the first group of plates overlapping the outer end portion of the second group of plates, a first and second series of circumferentially spaced radially disposed plungers slidably carried by the walls of the container and connected to the outer end portions of the first and second groups of plates, another series of circumferentially spaced radially disposed plungers carried by the walls of the container and connected to the inner end portions of both groups of plates, and means disposed adjacent the support for engaging and reciprocating all of said series of plungers during rotation of said container.

HARVEY PHILLIPS.
